UNITED STATES PATENT OFFICE.

EDWARD H. McCLOUD, OF COLUMBUS, OHIO.

CHANNEL FOR FIRE-SHUTTERS.

1,196,006.

Specification of Letters Patent. Patented Aug. 29, 1916.

Application filed October 28, 1912. Serial No. 728,032.

To all whom it may concern:

Be it known that I, EDWARD H. McCLOUD, a citizen of the United States, residing at Columbus, in the county of Franklin and 5 State of Ohio, have invented a certain new and useful Improvement in Channels for Fire-Shutters, of which the following is a specification.

The chief object of this invention is to 10 provide improved means for holding a metallic channel, guide or other member for a fire shutter, curtain or the like so that it may expand when subjected to the heat of fire and be maintained in substantially 15 straight or serviceable condition notwithstanding its expansion by heat.

The invention is embodied in the examples herein shown and described and then pointed out in the claims.

20 In the accompanying drawings—Figure 1 is a plan and horizontal sectional view looking down on one form of the invention. Fig. 2 is an elevation of the form of channel shown in Fig. 1 but on a smaller scale. Fig. 25 3 is a plan and horizontal sectional view looking down on another form of the invention. Fig. 4 is a horizontal section on the line $x-x$ Fig. 5 and Fig. 5 is an elevation of the form of channel illustrated in Figs. 3 30 and 4 but on a smaller scale.

Referring first to the form of the invention shown in Figs. 1 and 2 the channel is made of an inner strip 6, a spacer member 7 and an outer strip 8 riveted together by several rivets as at 9 so as to form at one side a longitudinal channel or way 10 for the sliding edge of the shutter or curtain and a longitudinal space at the opposite side for the holding members or blocks 11 which fit 40 in said space. The blocks 11 have shanks 11^a that project beyond the strip 8 and are perforated for the passage of securing bolts 12 turned into the wall or into the nuts of ordinary expansion shells 13 set into the 45 wall at 14. The block 11 is also shown to have a teat 11^b that projects into mortar space of the wall to prevent it from tilting on the shank of the bolt. There can be several of the blocks 11 suitably spaced to afford 50 support for the channel or guide, but the channel or guide is shown as attached to the wall with the uppermost of the blocks 11 only as by means of a set screw 15. The screw or fastening 15 holds the channel from

longitudinal movement in normal conditions 55 but permits it perceptibly to expand when subjected to adequate heat of fire.

In Figs. 3, 4 and 5 the outer channel forming member 16 is shown as bent so as to form space for the holding blocks that 60 is closed when the channel is placed against the wall. 17 designates the holding block. In this form the bolt 18 for securing the channel against movement in normal conditions can be passed through the outer channel forming member 16 and the uppermost 65 block and the other blocks can be secured by screws or bolts 19 having their heads countersunk in the blocks so as to permit the channel to expand with reference to such 70 blocks. Holes at 20 in the channel forming member are provided for the withdrawal of the securing bolts 19. The extension of the outer channel member so as to cover two sides of the blocks affords a stable connection 75 between the channel and the block.

What I claim is—

1. The combination with a channel or like member subject to longitudinal expansion by the heat of fire, of means for securing 80 said member in position consisting of a holder embraced on two sides by portions of said channel member and means for securing said member at one point to said holder. 85

2. The combination with a channel or like member subject to expansion by the heat of fire, of means for securing said member consisting of a holder embraced on two sides by portions of said member, and means for 90 securing said channel member at a fixed point so as to be expansible by adequate heat with reference to the holder.

3. The combination with a channel or like member subject to expansion by the heat of 95 fire, said member provided with an opening, of means for securing said member consisting of a holder embraced by a portion of said member, means operable through said opening for securing the holder in position, 100 and means for securing said member at a fixed point so as to be longitudinally expansible with reference to said holder by adequate heat.

EDWARD H. McCLOUD.
